(57) **CLAIM**

The ornamental design for an x-ray apparatus for medical treatment, as shown and described.

DESCRIPTION

FIG. 1 is a front, top and right side perspective view of an x-ray apparatus for medical treatment, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; the opposite side being a mirror image thereof; and,

FIG. 7 is a perspective view thereof with a compression holding plate section, stand and c-arm in an alternative position.
